COATING METHOD

Charles H. Dennison, Quincy, Mass., assignor to
 American Rubber Company, Cambridge, Mass.,
 a corporation of Massachusetts

Application July 14, 1931, Serial No. 550,639

1 Claim. (Cl. 91—68)

In the manufacture of coated sheets of material, particularly coated textile fabrics, it has been customary to use a doctor knife with a straight, smooth and continuous bearing edge arranged to press against the fabric. It is common to position a base roller or support under a doctor knife of this character in order to provide a base surface against which the fabric may be held during the application of the coating materials to the opposite surface by the knife. Sometimes the fabric is passed under such a knife without using a supporting roll and subsequently pulled upwardly under tension in order to enable the knife to frictionally engage the surface and scrape a coating composition thereagainst. These expedients have been satisfactory to some extent but certain disadvantages have been manifest in their adaptation to commercial manufacture. If the coating liquid is non-viscous and applied between a doctor knife and a supporting roll, it is quite likely to strike through the fabric and accumulate on the supporting roll or surface, resulting in difficulty in handling as well as a faulty and undesirable product. On the other hand the amount of coating material applied to a fabric by drawing it against a doctor knife of the character described is limited by the tension required to be placed upon the fabric in order to keep its surface in continual contact with the edge. If a high degree of tension is used only a small amount of coating material is actually applied, and it is necessary to build up a coating of desired thickness by many operations. If a low degree of tension is used, the fabric may not be positively held against the knife and an uneven coating may result.

An object of this invention is to overcome the difficulties above alluded to and to enable the application of more liquid coating material than has heretofore been possible, onto an advancing sheet and in one operation.

Another object is to make the amount of liquid coating material capable of application to sheets, for instance fabrics, independent of the tension to which the fabric is subjected to press it against the applying means.

Other objects and advantages of the invention will more clearly appear when reference is had to the following specification and claim.

The invention involves the use of a spreading device of novel nature which is constructed to provide a discontinuous edge made up of a number of bearing or doctor surfaces for contact with the material to be treated and a number of grooves of regulated width and depth arranged there-

between in order to permit a regulated flow of liquid coating composition. The bearing surfaces may be arranged at a slight angle to the travel of the sheet but are preferably substantially parallel with it. Their purpose is to contact with the sheet and continually hold the same a predetermined distance away from the inner surfaces of the grooves, allowing the coating composition to flow through the grooves, whose size governs the thickness of the application.

The invention may satisfactorily take the form of a threaded bar like that illustrated in the enlarged elevation of Fig. 1. This may be mounted on a base member in the manner shown in perspective in Fig. 2.

Fig. 3 shows diagrammatically how the invention may be utilized in the coating of sheet material.

The bar 1 may be provided with screw threads 3 and intermediate grooves 2, the top of the threads being preferably filed off as indicated in Fig. 1. The bar may be mounted on a member 6 provided with a groove 4 into which it may be fixed by suitable means. It is of course understood that the bar 1 which is illustrated is merely a convenient way of making a grooved mechanism and that any type of grooved spreader bar or strip which is provided with a proper number of grooves of required size and provided with suitable bearing surfaces may be used without departing from the principles herein laid down.

As in Fig. 3 the sheet 7 may be led under a device 8 which feeds the desired amount of coating composition to a reservoir or bank 9 of the composition confined by the upper surface of the sheet material and by the spreader bar 1. This may be regulated so that the composition collects in the space between the sheet 7 and the bar 1 but does not flow over the stops or guides 10 provided at each side of the apparatus. The sheet is drawn under the spreader bar 1 and the coating composition is applied to the sheet at spaced intervals by virtue of the grooves or channels in the spreader bar. The composition thus applied flows together in the form of a continuous uniform film

during the travel of the sheet to a suitable drier shown diagrammatically at 11, and from which the dried and coated sheet travels to a winding reel 12 which may be driven by suitable means (not shown) for winding the coated material at a uniform speed.

The material may be festooned in a drier by the use of well-known looping devices, if desired. As an example a latex composition may be fed as the coating material and in this case it is preferable to regulate the viscosity

of the latex to an extent sufficient to enable it to flow together again after passage through the grooves or channels which distribute it in a continuous uniform film. The height and width of the grooves may be adjusted to give the required flow. Various factors such as the consistency of coating material and the size of the grooves, may of course be varied to suit conditions, and these factors must be considered in connection with the 10 specific type of materials treated.

It should be noted that the amount of coating composition thus applied in uniform manner to a sheet material is practically independent of the pressure of the sheet surface against the doctor 15 bar, it being necessary only to nominally tension the material against the bar. As the amount of the coating material applied may be regulated by the size of the grooves, it is possible to obtain relatively thick films of uniform caliper in one operation, eliminating the necessity for successive 20 coatings and intermediate drying operations. When latex is used as a coating composition, the

internal structure is not disturbed by appreciable friction against the bearing surfaces, the material easily flowing through the grooves and filling the spaces left by the bearing surfaces by virtue of the separate streams flowing together again.

Having thus described my invention, what I claim and desire to protect by Letters Patent is:

The process of forming a layer of liquid coating composition on travelling sheet material which comprises passing said sheet material under tension under a grooved spreader bar, supplying a coating composition to a reservoir or bank of the same confined by the upper surface of the sheet and by the spreader bar whereby the coating composition flows through the grooves of the spreader bar and is distributed upon the sheet at spaced intervals as the sheet travels under the spreader bar, and allowing the thus applied composition to flow together to form a continuous substantially uniform film.
